COMBINED SOLE AND HEEL UNIT FOR FOOTWEAR

Aubrey Askew, Southport, England, assignor to Dunlop
Limited, St. James, London, England

Filed Mar. 9, 1973, Ser. No. 339,845

Claims priority, application Great Britain Sept. 18, 1972

Term of patent 14 years

Int. Cl. D2—02

U.S. Cl. D2—320

FIG. 1.

FIG. 2.

FIG. 3.

FIG. 1 is a bottom plan view of a combined sole and heel unit for footwear showing my new design;

FIG. 2 is a fragmentary cross-sectional view taken on the line 2—2 of FIG. 1; and

FIG. 3 is a fragmentary cross-sectional view taken on the line 3—3.

I claim:

The ornamental design for a combined sole and heel unit for footwear, as shown.
